UNITED STATES PATENT OFFICE.

WILHELM SCHMIDT, OF WILHELMSHÖHE, GERMANY.

SUPERHEATER.

SPECIFICATION forming part of Letters Patent No. 792,853, dated June 20, 1905.

Application filed November 7, 1904. Serial No. 231,759.

To all whom it may concern:

Be it known that I, WILHELM SCHMIDT, a subject of the King of Prussia, German Emperor, and a resident of Wilhelmshöhe, near Cassel, 5 in the Province of Hesse-Nassau, German Empire, have invented certain new and useful Improvements in Superheaters for Heating Tube-Boilers, of which the following is an exact specification.

10 My invention relates to superheaters for heating tube-boilers, such as are used for locomotive, automobile, ship, or similar purposes, and has for its purpose to utilize the combustion-gases in a most perfect manner by placing ring-tubes serving as superheaters into the flues of the tube-boilers. These ring-tubes are provided with return-channels, leading the steam to be superheated in one direction and then in the other through the tubes. The 15 ring-tubes are so arranged within the flues that the heating-gases flow through the interior of the ring-tubes, thereby heating the steam to be superheated. Such superheaters may be arranged in heating tube-boilers of 20 ordinary kind to be put up, or already-finished tube-boilers may subsequently be fitted out with such superheaters by substituting some of the flues of the boiler by larger flues, so as to create within the flues the space necessary 25 for subsequently putting in the superheating ring-tubes. Such superheaters have the advantage that the tubes can easily be cleaned, especially as the inner diameter can be made comparatively great. Instead of leading the 30 heating-gases only through the interior of the ring-tubes, these latter may be so arranged within the flues that the heating-gases also flow along the outside of the superheater-tubes. This latter is a most effective arrangement, as 35 the heating-gases first heat the ring-tubes from the inside, secondly from the outside, and thirdly they heat at the same time the flues. Such constructional forms are shown 40 in the accompanying drawings as matters of example, in which—

Figure 1 shows the general arrangement of a superheater according to my invention within a heating tube-boiler. Fig. 2 shows a front view of the superheater. Fig. 3 shows how 45 to place a superheater ring-tube into a flue.

Figs. 3^a and 3^b are cross-sections through the tube according to Fig. 3. Figs. 4 and 5 show similar views as Fig. 3, but illustrate different means for connecting the ring-tube with its steam-chambers. Fig. 6 shows a ring-tube 55 provided with sector-like inside channels. Figs. 6^a and 6^b are cross-sections through the arrangement according to Fig. 6.

In the drawings, *a* represents flues mounted in the tube-boiler body *c*.
60

b b' are two steam-chambers, chamber *b* being connected by pipe *x* to the steam-dome *c'*.

r represents superheater ring-tubes placed into some of the flues.

The ring-tubes according to Fig. 3 consist 65 of the ring-tube proper, having an outside tube *r* and an inside tube *r'*. Into the annular space between *r* and *r'* a tube *r''* is placed, so as to create two channels, one of which is connected to the steam-chamber *b*, whereas 70 the other discharges into the chamber *b'*. The working of this arrangement is as follows: The heating-gases generated in the fire-box *c'* of the boiler enter the flues at the left-hand side, as indicated by arrows. In these flues, 75 which are provided with superheater ring-tubes, the heating-gases are divided into two separate gas streams, one passing through the interior of the superheater-tubes and the other along outside of these tubes. The gases then 80 leave the flues and tubes and enter into the smoke-box *m*. The steam to be superheated flows through pipe *x* into chamber *b*, enters the ring-tube through the openings *o*, flows within these tubes to the left, then passes 85 through the space *q* at the left-hand end of the tubes over to the outside channel, and flows through the same back to the right, enters through openings *o'* the chamber *b'*, from which the steam, now superheated, is led to its 90 place of destination.

In the arrangement according to Fig. 3 the ring-tubes are directly put into the steam-chambers *b* and *b'*, whereas Fig. 4 shows special conical tightening-tubes *s* between the 95 ring-tube ends and the walls of the steam-chambers, thereby facilitating the tightening and exchanging of the ring-tubes. In the arrangement according to Fig. 5 special packing-rings *l l'* are arranged, which are pressed 100

2
by a stuffing-box against the end of the superheater-tube and the steam-chamber walls, so as to give a perfect tightening.

In the arrangements according to Figs. 3 to 5 the partition between the annular space of the superheater-tubes for obtaining return-channels within these tubes is formed by a heat-insulating double tube. In Fig. 6 another device is shown for obtaining return-channels within the annular space of the superheater-tubes. This space is divided by four longitudinal divisions into four sector-like channels, two of which, i i' , are connected at the right end to the steam-chamber b , whereas the right-hand ends of the sector-like channels i i' are connected to the steam-chamber b' . At the left-hand end both pairs of steam-channels i i' i i' are connected with one another by the end spaces q . The steam to be superheated again enters from the steam-chamber b through the openings o , the channels i i' flows through these sector-like channels to the left, enters through q the channels i i' , flows to the right, and the steam, now superheated by the heating-gases flowing through the interior, as well as along the outside of the superheater-tubes, leaves these latter through the openings o' and can then be led from the chamber b' to the place where it is to be used.

In the devices according to Figs. 3 to 5 the steam is first heated by the gases flowing through the interior of the superheater-tubes and then is further superheated on its way through the outside channel by the heating-gases flowing outside along the tubes, the heat-insulating double tubes r r' preventing that the steam flowing through the inside channel between r and r' cools the more superheated steam stream flowing through the outside channel between r and r' into the steam-chamber b' . The device according to Fig. 6 is of more simple construction, as there are no heat-insulating double tubes placed into the superheater-tubes, the steam flowing to the left and then back to the right, being on its whole way heated simultaneously by both the heating-gases flowing through the interior of the tubes and those flowing along outside the superheater-tubes.

Fig. 1 further shows two flaps p p , by means of which that space into which the gases flowing along the outside of the superheater-tubes enter can be cut off from the smoke-box m . If the flaps are closed, the heating-gases will only flow through the interior of the superheater-tubes. Furthermore, flaps can be provided for cutting off the connection between the interior of the superheater-tubes—that is to say, the interior of the inner tube r' , through which heating-gases are flowing, and the chamber m by means of closing members. These may be suitably connected to the blast-pipe, so that in working the blast-pipe the

flaps are closed, whereas they are opened if 65 the blast-pipe is cut off.

Having thus fully described the nature of my invention, what I desire to secure by Letters Patent of the United States is—

1. In a heating tube-boiler, the combination 70 of the boiler-body proper, with a set of flues, superheater ring-tubes so placed into a number of the flues as to lead heating-gases through the interior of said tubes, these latter being provided with channels for leading 75 the steam to be superheated forward and backward, substantially as described and for the purpose set forth.

2. In a heating tube-boiler, the combination 80 of the boiler-body proper, with a set of flues, superheater ring-tubes so placed into a number of the flues as to lead heating-gases through the interior of said tubes, whereas at the same time the heating-gases pass along 85 the outside of these ring-tubes, the latter being provided with channels for leading the steam to be superheated forward and backward, substantially as described and for the purpose set forth.

3. In a heating tube-boiler, the combination 90 of the boiler-body proper, with a set of flues, superheater ring-tubes so placed into a number of the flues as to lead heating-gases through the interior of said tubes, whereas at the same time the heating-gases pass along 95 the outside of said ring-tubes, thereby heating the same from outside, the ring-tubes being provided with channels for leading the steam to be superheated forward and backward, these channels being formed by a heat-insulating tube concentrically placed between the outer and the inner wall of the superheater-tube, substantially as described and for the purpose set forth.

4. In a heating tube-boiler, the combination 105 of the boiler-body proper, with a set of flues, superheater ring-tubes so placed into a number of the flues as to lead heating-gases through the interior of said tubes, whereas at the same time heating-gases pass along the 110 outside of said ring-tubes, thereby heating the same, these tubes being provided with channels for leading the steam to be superheated forward and backward, these channels being formed by a heat-insulating tube concentrically placed between the outer and the inner wall of the superheater-tube, the insulating-tube consisting of two tubes concentrically placed close to each other, substantially as described and for the purpose set 120 forth.

In witness whereof I have hereunto set my hand in the presence of two witnesses.

WILHELM SCHMIDT.
